UNITED STATES PATENT OFFICE.

ALICE SMYTHE JAY, OF BROOKLYN, NEW YORK.

MUSIC-ROLL FOR PIANO-PLAYERS AND METHOD OF PRODUCING SAME.

1,381,641.

Specification of Letters Patent. Patented June 14, 1921.

Continuation of application Serial No. 90,698, filed April 12, 1916. This application filed August 23, 1920. Serial No. 405,255.

To all whom it may concern:

Be it known that I, ALICE SMYTHE JAY, a citizen of the United States, residing at Brooklyn, county of Kings, and State of New York, have invented certain new and useful Improvements in Music-Rolls for Piano-Players and Methods of Producing Same, of which the following is a specification.

10 My invention relates to improvements in the method of producing music rolls for automatic pianos, the same to be used in conjunction with the reproduction of moving picture presentations.

15 The present application is to be considered a continuation of my pending application Serial No. 90,698 to the extent of the disclosures therein.

Heretofore, so far as I am aware, the usual method of producing music rolls for such use has been very unsatisfactory in that it consumes much time and labor and it has been almost impossible to get the roll properly synchronized with the changing scenes 25 of the film.

The object of my invention is to provide an improved method for producing music rolls of the character mentioned whereby the rolls so produced will reproduce music in 30 harmony with the reproduction of the picture with which it is to be used. A further object of my invention is to provide a method for producing said rolls whereby the cutting of the master sheet is completed with 35 one operation and that while viewing the picture with which it is to be employed. A further object of my invention is to provide a music roll of the usual length (approximately ninety feet) which will synchronize 40 correctly with a complete film reel of the usual length (approximately one thousand feet.) Heretofore, so far as I am aware, this has not been possible and it has been necessary when presenting a thousand foot 45 reel to use several music rolls to accompany the same, thereby necessitating changing of the rolls during the presentation of the picture. A further object of my invention is to provide a music roll of the character mentioned 50 provided with suitable indicia whereby the operator of the musical instrument shall be advised of the changes in the scene so as to be able to keep the music synchronized with the picture in the event that 55 the operator of the projecting machine is operating the same out of the normal time;

or in the event that the picture film has been repaired with portions thereof cut out as is common. Other objects will appear hereinafter.

To understand my invention, the usual method of recording master sheets should be borne in mind. In recording these sheets a recording machine is provided through which the blank, unperforated sheet is fed at 60 a uniform speed. This recording machine is connected, usually electrically, to a piano, and the musician plays the piano and in so doing operates the recording machine. The recording machine may be of either of the 65 two general forms used for this purpose, one of which cuts the necessary apertures in the music sheet and the other of which indicates on the sheet where the apertures are to be cut to form the master roll. This is old and 70 forms no part of my invention except in so far as the employment of such a recording device is necessary in the complete method. For this reason, the recording machine and piano are not illustrated in the drawings as 75 this is well understood by those familiar with the art. In carrying out my invention, a piano connected to a cutting machine is positioned in front of a screen and the musician is seated at the piano so as to be able 80 to watch the picture thrown upon the screen. An assistant stands beside the musician, for a purpose hereinafter mentioned, and a stenographer is also positioned so as to take dictation from the musician. As the picture is 85 thrown upon the screen, the musician plays music suitable to the screen, being shown, and changes the music to suit the change of scenes. This music may be improvised as 90 the scenes appear, or may be played from written or printed music. With each change 95 of scene or prominent act in the scene, the musician calls such change or act which are taken down by the stenographer in sequence. The announcements on the screen are also 100 dictated in sequence with said acts and scenes and these are also taken in order by the stenographer. With each call of an announcement or a scene or act, the afore-mentioned 105 assistant, standing beside the musician with a finger on one of the keys of the piano, preferably the highest one, operates said key to produce a symbol or indicia upon the sheet being cut so that after the sheet is completely 110 cut the dictated announcements, scenes, etc., may be printed in proper position upon the sheet. After the sheet is completely cut and

printed as above mentioned, it is run through a piano player simultaneously with a reproduction of the picture to insure that the cues or indicia thereon are correctly positioned, 5 after which the master sheet is complete and ready to be used in the reproduction of other rolls for commercial use.

My invention will be more readily understood by reference to the accompanying 10 drawings forming a part of this specification and in which—

Figure 1 is a fragmentary view of a portion of the cut master sheet as it comes from the cutting machine,

15 Fig. 2 is a similar view thereof with the indicia inserted, and

Fig. 3 is a sheet prepared by the stenographer from which the indicia is obtained for placing upon the music roll.

20 Referring now to the drawings, 1 indicates a portion of the music roll having the apertures 2 cut therein by the usual cutting machine. I prefer to use a recording machine which cuts the sheet, but as heretofore 25 explained, the use of any recording machine in the process comes within the scope of my invention, so that wherever I mention that the sheet is cut by the recording machine it is to be understood that this also contemplates 30 marking the sheet to be subsequently cut. 3 and 4 are apertures cut on the edge of the sheet by the aforementioned assistant at the time the dictation is given by the musician. The sections of the music roll and of the 35 stenographer's transcribed sheet shown in the drawings is the reproduction of an actual roll and sheet, the same being the first portion of Part II of a reproduction of East Lynne. In producing the same, as soon as 40 announcement numbered 17 was shown on the screen, the musician dictated "Announcement 17—Judge Hare." This was taken down by the stenographer and simultaneously with said dictation of "Announcement" 45 the assistant struck two short strokes upon the high key of the piano producing the two apertures 4^a shown on Figs. 1 and 2. When the picture showed Dick Hare and his father, the musician, continuously playing suitable 50 improvised music, dictated "Dick Hare and father" which was taken down by the stenographer and the said assistant struck one quick sharp stroke upon the high key of the piano, producing the one aperture 3^a. 55 This was continued throughout the production of the picture and it will be seen that the stenographer's sheet of Fig. 3 will tally with the music sheets of Figs. 1 and 2. After the roll is completed suitable stamps are 60 made from the stenographer's sheet and these are placed on the sheet opposite the apertures 3 and 4, as shown in Fig. 2, said apertures indicating the proper positions of the various inscriptions.

65 In order that the reproduction of the mu-

sic shall be synchronized with the exhibition of the picture, the roll is marked with the proper tempo as indicated at 5 in Fig. 1. If the operator of the piano player sets the instrument to the tempo indicated on the 70 roll, and the projection machine is operated at the standard speed of 16 to 1, the music will be perfectly synchronized with the picture. However, should the operator of the 75 projecting machine speed up or slow down the picture, the operator of the piano player can keep the music synchronized with the picture by attention to the cues stamped upon the rolls. These cues also facilitate the synchronization of the music to the picture 80 when the film has been repaired with portions thereof cut out. Also, by setting the piano player to the indicated tempo, the same being the tempo at which the music was originally played, the music roll will be 85 reproduced in exactly the same time as that taken for the reproduction of the film reel, thereby avoiding the necessity of changing the music roll during the reproduction of the reel. 90

I claim:—

1. The method of producing music rolls for the purpose mentioned which consists in playing suitable music while viewing the reproduction of the picture, thereby recording the music on a sheet by the usual method; and simultaneously indicating on the music roll indicia for positioning cues, substantially as described. 95

2. The method of producing music rolls 100 for use with moving pictures, consisting in playing suitable music and thereby recording the music on a sheet with a recording machine while viewing the reproduction of the picture; indicating on the roll with the recording machine the position for verbally announced cues; then printing the announced cues on the sheet in the positions indicated by the recorded indicia, substantially as described. 110

3. The method of producing music rolls for use with moving pictures, consisting in playing suitable music and thereby recording the music on a sheet with a recording machine while viewing the reproduction of the picture; indicating on the roll with the recording machine the position for cues; then printing the cues on the sheet in the position indicated by the recording indicia, substantially as described. 115

4. A music roll for piano players for use in conjunction with moving picture presentations, having scene cues indicated thereon, substantially as described. 120

5. A music roll for piano players for use 125 in conjunction with moving pictures having indicia thereon to facilitate synchronizing the music with the picture, substantially as described.

6. A music roll having perforations form- 130

ing a record for a musical instrument, said record being formed synchronously with a moving picture, the melody of the music being determined by the character of the picture on the film, and cues on said roll indicating changes of time synchronizing the music with the character of the film scenes being reproduced.

7. A music roll having perforations forming a record for a musical instrument, said record being formed synchronously with a moving picture, the melody of the music being determined by the character of the pictures on the film, cues on the roll, each of 15 said cues having a direct significance in connection with the picture, advising the operator in advance the next scene to be presented in the picture.

8. A music roll having perforations form-

ing a record for a musical instrument, said record being formed synchronously with the reproduction of a certain moving picture film, the melody of the music being determined by the pictorial illustrations of the pictures on the film, cues on said roll indicating in advance the next scene to be presented in the picture and synchronizing the music on the roll to the character of picture being shown, and cues on said roll indicating the changes of time.

In testimony whereof I have signed my name to this specification in the presence of two subscribing witnesses.

ALICE SMYTHE JAY.
